TO FAIRBANKS, MORSE & COMPANY, OF CHICAGO, ILLINOIS, A CORPORATION OF
ILLINOIS.

LUBRICATOR.

1,275,427.

Specification of Letters Patent. Patented Aug. 13, 1918.

Application filed October 10, 1917. Serial No. 195,675.

To all whom it may concern:

Be it known that we, FRANKLIN G. HOBART, and CHARLES B. JAHNKE, citizens of the United States, residing at Beloit, in the 5 county of Rock and State of Wisconsin, have invented a certain new and useful Improvement in Lubricators, of which the following is a specification.

Our invention relates to lubricators and is 10 intended primarily to be used in connection with internal combustion engines, especially those having a closed crank case. The object of the invention is to provide simple and effective means, free of valves or other moving 15 parts, for lubricating coacting elements of the engine; for example, the cam mechanism which controls the operation of the engine.

The object is accomplished by the mechanism illustrated in the accompanying drawings, in which:

Figure 1 is a sectional elevation of cam mechanism inclosed within a housing and equipped with a lubricator embodying the invention, the plane of section being indicated by the line 1—1, Fig. 2.

Fig. 2 is an elevation of the parts shown in Fig. 1 drawn on a decreased scale and showing them in their relation to the crank case of a stationary internal combustion engine.

The cam mechanism shown forms the subject of a co-pending application filed by Franklin G. Hobart on the 8th day of October, 1917, Serial Number 195,254.

Similar numerals refer to similar parts in the two views.

The present invention is not concerned with the specific type of cam mechanism, for it will be understood that the lubricator may 40 be employed to lubricate a variety of co-acting parts. The cam mechanism is therefore used for the sake of illustration only and it is sufficient for the present purpose to say that it consists of a cam 1 mounted upon the engine shaft 2 and actuating a number of anti-friction rollers 3 which produce certain mechanical motions. The parts mentioned are inclosed within a housing 4 which is oil-tight, especially at the bottom where it normally contains a supply of lubricating oil, as indicated.

A pipe 6 leads from a point inside of the engine crank case 7 to the bottom of housing 4. It then passes up through the housing

and up to a point above the level of the oil 55 therein. The upper end 8 of pipe 6 is open and points toward the parts to be lubricated. The particular design of these parts may be varied as will be readily understood by those skilled in the art of machine design, the essential idea being that the pipe 6 leads in through the housing so as to make oil-tight connection therewith and to pass upward through the oil collected at the bottom of the housing. 60 65

A small aperture 10 is formed in pipe 6 above the bottom of the housing and below the normal level of the lubricating oil. This admits lubricating oil to the inside pipe, as will be explained. 70

In the construction shown, the end of the pipe which is in the inclosed crank case is higher than the level of the lubricating oil, thus avoiding any danger of the oil flowing from the housing back to the crank case of 75 the engine.

The principle of operation is as follows: The crank case is inclosed in the sense that the term is commonly employed in the art. The result is that the engine piston produces 80 pulsations of air in the crank case—usually first a partial vacuum and then a compression. This produces first a suction and then an air blast in pipe 6. The suction draws a small quantity of lubricating oil through 85 aperture 10 into the pipe and the succeeding impulse or blast forcibly ejects this oil up through the open mouth of the pipe 10 directed toward the parts to be lubricated. There is consequently a constant “spitting” 90 of oil, so to speak, out through the end of the pipe and this lubricates not only the parts directly in line with the pipe but also those in the neighborhood, for under ordinary circumstances, the oil will be thrown to 95 the various parts of the housing.

It will be understood that it is not essential that there be actual suction at any time in pipe 6. It is sufficient if there are intermittent impulses or blasts of air traveling 100 through the pipe; and it is not essential that the aperture 10 be so small that the oil will not flow through it by gravity. Under normal conditions, however, the oil will first be sucked and then forcibly ejected from the 105 pipe by the action of the air, due to the action of the engine piston or pistons working in the inclosed crank case.

Having thus described our invention, what we claim as new and desire to secure by Letters Patent, is:—

1. A lubricator having a container for lubricating oil, a pipe leading up through the bottom of the container to a point above the level of the oil, the pipe having an aperture in the side for admitting oil, and means for producing an intermittent blast of air upward in said pipe.
2. In a lubricator for an internal combustion engine having a closed crank case, the combination, with said crank case, of a container for oil, said container inclosing the parts to be lubricated, and a pipe leading from said case up through the oil in the container, the pipe having an opening in the side for the admission of oil to be ejected through the end of the pipe.
3. In a lubricator for an internal combustion engine having a closed crank case, the combination, with said crank case, of a container for oil, said container inclosing the parts to be lubricated, and a pipe leading from said case up through the oil in the container, the pipe having an opening in the

side for the admission of oil to be ejected through the end of the pipe, the end of the pipe which is in the crank case being above the end which is in the container.

4. The combination, with an internal combustion engine having a closed crank case and a piston producing alternately suction and compression in the crank case, of cam mechanism operated by the engine shaft, a housing inclosing said cam mechanism, said housing being adapted to contain fuel oil, a pipe leading from the inside of the crank case to the inside of the housing and passing upward through the lubricating oil in the housing and pointing in the general direction of the cam mechanism, the upper end of the pipe being open and above the level of the oil, and the pipe having a small hole in the side below the level of the oil whereby a small quantity of oil is first sucked into the pipe and then forcibly ejected upward in the housing to lubricate the cam mechanism.

In witness whereof we have hereunto subscribed our names.

FRANKLIN G. HOBART.
CHARLES B. JAHNKE.
